UNITED STATES PATENT OFFICE.

WILLIAM H. WALDRON, OF NEW BRUNSWICK, NEW JERSEY.

BLOCK-PRINTING MACHINE.

1,283,378.

Specification of Letters Patent. Patented Oct. 29, 1918.

Application filed January 19, 1916. Serial No. 73,014.

To all whom it may concern:

Be it known that I, WILLIAM H. WALDRON, a citizen of the United States, and a resident of New Brunswick, county of Middlesex, State of New Jersey, have invented certain Improvements in Block-Printing Machines, of which the following is a specification.

My invention relates to certain improvements in machines for printing oilcloth and similar materials in which blocks are used to make the impressions, the blocks being mounted on reciprocating carriers actuated, in the present instance, by cams.

The object of the invention is to provide means for holding the independent printing blocks out of action and to provide electric mechanism for actuating the latch.

In the accompanying drawing:

Figure 1 is a side view of one section of a block printing machine, illustrating my invention;

Fig. 2 is a front view showing a series of push buttons or switches, and

Fig. 3 is a view of a form of commutator that may be used in connection with my mechanism.

Referring to the drawing, 1 is the frame of the machine having guides 2 of the block carrier 3. This block carrier consists, in the present instance, of a pair of horizontal beams 4 connected to side members 5, which are adapted to guides 2 in the frame of the machine and are slotted at 6 for the passage of the cam shaft 7 driven in any suitable manner. On this cam shaft are cams 8 of the peculiar shape shown in the drawing, and each cam has a raised portion 9 which carries the printing block above the line of the inking roller 10. This inking roller is mounted on a carriage 11, which is adapted to reciprocate in the ordinary manner under the carrier and to ink the projecting portions of the printing block 12 which is secured to the under side of the carrier 3. The ordinary method of holding the carrier in the elevated position is to use a hand latch. This is uncertain, as the action of the operator's hand is sometimes too slow to actuate the latch when the block is at its highest point. If not caught at the proper time, the block prints a repeat whe it should not. Furthermore, it is necessary for the operator to walk from one hand latch to another in order to lock certain blocks out of action at the same time.

The mechanism which I will now proceed

to describe is rapid and accurate, and the mechanism of two or more blocks may be operated simultaneously, if desired.

At the side of the block carrier is a detent 13 having an inclined end, which is adapted to enter a notch 14 and engage a shoulder on the side member 5 of the carrier. The detent is adapted to slide in bearings 15 and 16 respectively and has a coiled spring 17 which bears against an armature 18 secured to the detent so that the spring normally holds the detent out of engagement with the carrier. Mounted on the bearings 15 are magnets 19, which are so located in respect to the armature that when a current passes through the magnets the armature will be attracted and will move the detent against the pressure of the spring 17 into the path of the notch 14 so that the moment the notch comes in line with the detent, the detent will enter the notch and will retain the carrier in an elevated position clear of the inking roller. The cam 8 will travel under the roller 20 on the side members 5 of the carrier.

21 is an ordinary push button and the wires extend from the button to the magnets, and a battery is in the circuit in the ordinary manner. The push button can be located at any point desired away from the mechanism of the machine and, as machines of this type have a series of block carriers, the mechanism above described is duplicated and all of the push buttons may be located at a convenience point, as in Fig. 2, so that an operator, when he wishes to hold any one of the printing blocks out of action, simply presses the button of that particular block carrier and holds it until the detent is in engagement with the carrier. The block is arrested until the cam makes another complete revolution and the high part of the cam 9 will release the detent, if the circuit be open. The spring 17 will withdraw the detent, allowing the block to make an impression. While I have shown a detent on only one side of the machine, it will be understood that in large machines there will be a detent on each side thereof, the detents acting in unison.

Where certain blocks are to be drawn out of action in a given order a commutator may be used which will be driven from the mechanism of the machine and which will automatically project the detents and hold the blocks out of engagement during certain

periods of the printing operation. Such a commutator is illustrated in Fig. 3, in which 22 is a shaft driven from any point of the machine at the required speed, and on this 5 shaft is a series of disks 23. These disks have sections of insulating material so as to break the circuit at the proper intervals.

The material to be printed is fed intermittently through the machine and there is 10 usually a series of printing block carriers which are reciprocated to and from the material and mounted on each carrier is a printing block, which makes the impression. These blocks are supplied with color by reciprocating mechanism carrying rollers, which travel in contact with the surface of the blocks when the carriers are in the raised position, but, in order to hold the blocks 15 clear of this inking mechanism, when the carriers are out of action, the cam 8 has a raised portion which lifts the block carrier of the inking mechanism and if a push button, or switch, be pressed to energize the 20 magnets at one of the detents, that detent 25 will be forced out into engagement with the

block carrier, holding the carrier in the raised position, but, as soon as the cam makes a complete revolution and the block carrier is raised and the magnets are not energized, the spring retracts the detent and the carrier is allowed to move, the block 30 making an impression.

I claim:

The combination in a flat block printing machine, of a frame; a vertically reciprocating block carrier mounted on the frame; power mechanism for raising the block carrier; a printing block mounted on the carrier, said carrier having a shoulder; a sliding detent arranged to engage the shoulder 35 on the carrier and to hold the carrier out of action; an armature on the detent; magnets located so as to cause the detent to engage the carrier when the said magnets are energized; means for retracting the detent to allow the block to make an impression; and 40 a switch in circuit with the magnet for controlling the magnet.

WILLIAM H. WALDRON.
